US0D1034927S

(12) **United States Design Patent** (10) **Patent No.:** **US D1,034,927 S**
(45) **Date of Patent:** **** Jul. 9, 2024**

(54) **COVER**

(71) Applicant: **U.S. Aluminum, Inc.**, Wauwatosa, WI (US)

(72) Inventor: **John Geers**, Wauwatosa, WI (US)

(73) Assignee: **U.S. Aluminum, Inc.**, Wauwatosa, WI (US)

(**) Term: **15 Years**

(21) Appl. No.: **29/727,678**

(22) Filed: **Mar. 12, 2020**

(51) LOC (14) Cl. **23-01**

(52) U.S. Cl.

USPC **D23/267**

(58) **Field of Classification Search**

USPC D23/266, 267, 259, 260–263, 265; D25/136, 138, 236

CPC E04D 13/00; E04D 13/064; E04D 13/076

See application file for complete search history.

Assistant Examiner — Alfred A Addison

(74) Attorney, Agent, or Firm — Reinhart Boerner Van Deuren s.c.

(57) **CLAIM**

I claim the ornamental design for a cover, as shown and described.

DESCRIPTION

FIG. 1 is a perspective view of an embodiment of the claimed design for a metal cover;

FIG. 2 is a side view of the claimed design of FIG. 1; FIG. 3 is an opposite side view of the claimed design of FIG. 1;

FIG. 4 is an end view of the claimed design of FIG. 1; FIG. 5 is an opposite end view of the claimed design of FIG. 1;

FIG. 6 is a top view of the claimed design of FIG. 1; and, FIG. 7 is a bottom view of the claimed design of FIG. 1.

FIG. 8 is a perspective view of an embodiment of the claimed design for a metal cover;

FIG. 9 is a side view of the claimed design of FIG. 8;

FIG. 10 is an opposite side view of the claimed design of FIG. 8;

FIG. 11 is an end view of the claimed design of FIG. 8; FIG. 12 is an opposite end view of the claimed design of FIG. 8;

FIG. 13 is a top view of the claimed design of FIG. 8; and, FIG. 14 is a bottom view of the claimed design of FIG. 8.

1 Claim, 10 Drawing Sheets
